CLAIM

(73) Assignee: **Siemens Schweiz AG**, Zürich

The ornamental design for a building automation device housing, as shown and described.

(**) Term: **14 Years**

DESCRIPTION

(21) Appl. No.: **29/212,554**

FIG. 1 is a perspective view of the building automation housing;

(22) Filed: **Sep. 3, 2004**

FIG. 2 is a front view of the building automation housing;

(30) **Foreign Application Priority Data**

FIG. 3 is a top view of the building automation housing;

Mar. 12, 2004 (CH) 130577
Mar. 12, 2004 (EM) 000153028-0003

FIG. 4 is a typical side elevational view of the building automation housing;

(51) LOC (8) Cl. **10-04**

FIG. 5 is a bottom view of the building automation housing;

(52) U.S. Cl. **D10/50**

and,

(58) **Field of Classification Search** D10/49-50;
236/46 R, 47, 49.3, 51, 84, 94; 400/485
See application file for complete search history.

FIG. 6 is a back view of the building automation housing.
